EXCAVATING MACHINE

Rolf E. Ljungkull, St. Paul, Minn., assignor to
 American Hoist and Derrick Company, St.
 Paul, Minn., a corporation of Delaware

Application April 23, 1934, Serial No. 721,983

10 Claims. (Cl. 212—68)

This invention relates to an excavating machine, and the general object of the invention is to provide an excavating machine wherein will be incorporated various improved features and characteristics of construction novel both as individual entities of the machine and in combination with each other.

A further object is to provide an excavating machine which will include a bull gear, as well as a bull gear arrangement, of novel and improved construction.

A further object is to provide an excavating machine which will include a car body and a bull gear associated therewith in novel and improved manner.

A further object is to provide an excavating machine which will include a car body of novel and improved construction.

A further object is to provide an excavating machine comprising a car body, a revolvable platform upon said car body and supporting a mast structure, boom, bucket or dipper, operating mechanism, etc., and a novel and improved association of said platform with said car body, whereby the platform can be easily and conveniently revolved upon an axis for said platform carried by the car body.

A further object is to provide an excavating machine the platform of which will support an upper rail or rails riding rollers or wheels of a container ring of the excavating machine, which rollers or wheels in turn ride the operative rail of the bull gear of the machine, the whole constituting a novel and improved construction in excavating machines.

A further object is to provide in the excavating machine, a novel and improved construction of mechanism for revolving the platform about its axis upon the car body.

A further object is to provide an excavating machine which will include a platform, desirably having walkways thereon, of novel and improved construction.

A further object is to provide an excavating machine which will include a container ring with rollers or wheels constituting novel and improved construction in excavating machines.

A further object is to provide an excavating machine which will include a boom of novel and improved construction, and a new and improved mounting for the boom upon the platform of the machine.

A further object is to provide an excavating machine which will include a mast of novel and improved construction, and a new and improved

mounting for the mast upon the platform of the machine.

A further object is to provide an excavating machine which will include a novel and improved back brace mounted upon the platform of the machine in new and improved manner.

A further object is to provide in the excavating machine, a mast and a back brace mounted upon the platform of the machine, and means of novel and improved construction connecting upper portions of said mast and back brace with each other.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawings forming a part of this specification,—

Fig. 1 is a side elevational view of an excavating machine in which the features of the invention are incorporated, parts being omitted and broken away;

Fig. 2 is a top plan view of the machine, parts being omitted;

Fig. 3 is an enlarged elevational view of the platform of the machine, as seen from the left in Fig. 2;

Fig. 4 is a vertical, longitudinal sectional view of the machine, parts being omitted and broken away;

Fig. 5 is an enlarged horizontal sectional view, taken as on line 5—5 in Fig. 4, detailing features of the platform and the revolving mechanism therefor, as well as features of the mounting for the platform upon the car body;

Fig. 6 is an enlarged horizontal sectional view, taken as on line 6—6 in Fig. 4, detailing features of the bull gear and of the car body of the machine;

Fig. 7 is an enlarged vertical sectional view, taken as on line 7—7 in Fig. 6, detailing additional features of the bull gear and the car body;

Fig. 8 is a reduced horizontal sectional view, taken as on line 8—8 in Fig. 7, detailing features of the car body;

Fig. 9 is an enlarged vertical sectional view taken as on line 9—9 in Fig. 4, detailing features

of the container ring of the machine and showing one of the duplicate platform supporting rollers or wheels carried by said container ring;

Fig. 10 is an enlarged vertical, transverse sectional view, taken as on line 10—10 in Fig. 6, detailing still additional features of the car body;

Fig. 11 is a fragmentary plan view of the car body;

Fig. 12 is an enlarged vertical sectional view, taken as on line 12—12 in Fig. 6, further detailing features of the car body;

Fig. 13 is an enlarged vertical sectional view, taken on line 13—13 in Fig. 2, detailing features of the mechanism for revolving the platform upon the car body;

Fig. 14 is a side elevational view showing a continuation of the boom of Fig. 1, parts being broken away;

Fig. 15 is an enlarged fragmentary side elevational view detailing features of the boom;

Fig. 16 is a detail sectional view of the boom, taken on line 16—16 in Fig. 15;

Fig. 17 is a detail sectional view of the boom, taken as on line 17—17 in Fig. 16;

Fig. 18 is a view detailing the manner of attaching T-bars of the boom to angle bars thereof;

Fig. 19 is a sectional view, taken on line 19—19 in Fig. 1, disclosing a lower fragment of the boom in top plan as when swung toward horizontal position in said Fig. 1;

Fig. 20 is a top plan view of the upper or outer portion of the boom of Fig. 19, parts being broken away;

Fig. 21 is a detail sectional view of the boom, taken on line 21—21 in Fig. 19;

Fig. 22 is a detail sectional view of the mounting for the boom, taken on line 22—22 in Fig. 1;

Fig. 23 is a detail sectional view, taken on line 23—23 in Fig. 1, disclosing the back brace of the excavating machine in top elevation;

Fig. 24 is a sectional view detailing features of the mounting for the back brace upon the platform, taken on line 24—24 in Fig. 1;

Fig. 25 is a sectional view detailing features of the lower portion of the connection between the back brace and the mast, taken on line 25—25 in Fig. 1;

Fig. 26 is a detail sectional view, taken on line 26—26 in Fig. 1, disclosing the mast in top elevation;

Fig. 27 is a sectional view detailing features of the upper portion of the connection between the back brace and the mast, taken on line 27—27 in Fig. 1;

Fig. 28 is a detail perspective view disclosing a slotted end portion of an I-beam of the platform for receiving plates upon which the boom and mast are mounted; and—

Fig. 29 is a sectional view detailing features of the mounting for the mast upon the platform, taken on line 29—29 in Fig. 1.

With respect to the drawings and the numerals of reference thereon, the excavating machine includes a car body or frame 31 having bearings for axles 32 which rigidly support traveling wheels 33. The machine may be self, or otherwise, propelled along the track 34.

The car body or frame 31 is of the novel and improved construction very clearly disclosed in Figs. 1, 4, 6, 7, 8, 10, 11, 12 and 13. As there shown, said car body or frame includes longitudinally extending frame members 35 at the sides of the car body, and transversely extending frame members 36 at the ends of said car body. Each side frame member 35 consists of a pair of elongated

I-beams, denoted 37 and 38, respectively, having the body portions or webs 39 of said I-beams disposed vertically and parallelly with each other, and having the meeting edges of adjacent upper and lower flanges, denoted 40 and 41, respectively, of said I-beams welded together, as shown very clearly at 42 in Figs. 6, 7, 8 and 10. Portions of the meeting edges of the upper flanges 40 and lower flanges 41 are cut away, and metal 43 to weld said flanges together is placed in said 10 cut-away portions in any well known manner. Also at spaced apart intervals along the lengths of the side frame members 35, the connected I-beams are desirably reinforced by transverse webs 44 welded to the body portions or webs 39 15 and to the flanges of said I-beams, as well as by U-bars 45 and filler bars 46 between adjacent body portions or webs 39, the U-bars and filler bars being shown as riveted to the body portions or webs. The transverse webs 44, U-bars 45 and 20 filler bars 46 could be attached to the I-beams in a manner different from that shown. Each end frame member 36 consists of an I-beam extending between the side frame members 35, there being an end frame member 36 adjacent each end 25 of the car body in spaced relation to the outermost extremities of said side frame members 35. The end frame members 36 are perpendicular to the side frame members 35. As disclosed more clearly in Figs. 4, 6, 10, 11 and 13, the innermost 30 upper and lower flanges, denoted 47 and 48, respectively, of the side frame members 35 detachably support, as by screw bolts 49, plates 50 at the inner sides of the upper and lower flanges, denoted 51 and 52, respectively, of the opposite end 35 portions of each end frame member 36, and said plates 50 are welded to said upper and lower flanges 51 and 52, as at 53. The end frame members or I-beams 36 are desirably reinforced by transverse webs 54. Said end frame members or 40 I-beams 36 are themselves interconnected by spaced apart I-beams, denoted 55 and 56, respectively, extending lengthwise of the car body at opposite sides of the longitudinal center thereof. Opposite end portions of flanges of said I-beams 45 55 and 56 are detachably connected, as by bolts 57, to adjacent flanges of the end frame members or I-beams 36, the flanges of said I-beams 55 and 56 lying between the flanges of said I-beams 36. Also, each I-beam 55 and 56 includes transverse 50 webs 58 at the opposite ends thereof, which webs are bolted, as at 59 in Figs. 6 and 10, to the body portions or webs of the I-beams 36. As shown in Figs. 6, 10 and 11, a plate 60 is interposed between an upper flange of each I-beam 36 and the flanges 55 upon the adjacent ends of the I-beams 55 and 56, and said I-beams 55 and 56 are bolted as at 57 to said plates 60 as well as to the I-beams 36. A pair of reinforcing plates, denoted 61 and 62, respectively, extend transversely of the car body 60 at the opposite sides of the transverse center thereof, said plates 61 and 62 lying between the bodies or webs of the I-beams 55 and 56 and being welded or otherwise fastened to said I-beams 55 and 56. As shown more clearly in Figs. 6 and 12, four plates, each denoted 63, are bolted, as at 64, to the upper, outer flanges of the I-beams 55 and 56, said plates 63 being equally spaced from the vertical axis of the car body and at equal distances apart. Each plate 63 is welded 70 to a channel member 65, as at 66, and each of the four channel members 65 extends horizontally outwardly toward a corner of the car body. A relatively short I-beam 67 adjacent each corner 75 of the car body extends obliquely to the side and 75

end frame members 35 and 36 desirably at a forty-five degree angle to each frame member. The I-beams 67 may include reinforcing webs 68. An end portion of each I-beam 67 is suitably welded to an end frame member or I-beam 36 as at 69, and the upper and lower flanges of the opposite end portion of each I-beam 67 are welded to the upper and lower plates 50, as at 70. The body portion or web of each I-beam 67 is welded as at 71 to a vertical plate 72 which is detachably bolted, as at 73, to the body portion or web of the inner I-beam of each side frame member. Obviously, there are four vertical plates 72. In addition, there are four vertical plates 74 bolted as at 75 to the body portion or web of the inner I-beam of each side frame member to which the opposite end portions of each end frame member or I-beam 36 are welded as at 76. The outer ends of the channel members 65 are bolted as at 20 88 to plates 89 welded to the I-beams 67.

The axles 32 for the car wheels are mounted in the body portions or webs of the I-beams of the side frame members, as will be apparent, and the lower flanges of said I-beams of the side frame members are cut away, as denoted at 77 in Fig. 6, to accommodate the car wheels.

An important feature of the invention is a novel and improved bull gear associated with the car body or frame of the excavating machine in new and improved manner. The construction of the bull gear and its assembly with the car body or frame will be clear by reference to Figs. 1, 4, 6, 7, 10 and 13. As there disclosed, said bull gear consists of an inner annular portion 78 providing an internal, vertically disposed gear surface or toothed portion 79, an outer annular upstanding or vertical portion 80 providing an operating rail 81 of the bull gear constituting the lower rail of the excavating machine, and an annular horizontal portion or web 82 integrally connecting the lower parts of the portions 78 and 80. The bottom surface of the horizontal portion or web 82 is flat. As disclosed, the bull gear consists of two equal halves each extending 180°, and said halves of the bull gear are detachably connected to each other by bolts 83 arranged in reinforcing flanges or webs 84 upon the different halves of said bull gear at the meeting ends of the two halves. The bull gear includes additional reinforcing flanges or webs 84 at spaced intervals about its periphery. In practice, the bull gear can if desired be cast as a continuous circumferential member. Preferably, however, it is when so cast cut to provide two diametrical halves detachably connected in the manner as illustrated and described.

As disclosed, the bull gear is placed upon the car body or frame so that the end portions of the detachably connected halves thereof lie directly over the midlengths of the side frame members 35. When said bull gear is upon the car body or frame, the circumference of the horizontal portion or web 82 rests upon the upper flanges of the I-beams 36 and 67 as well as upon the upper flanges of the I-beams 37 and 38; that is, upon the side frame members 35. The bull gear is desirably welded, as at 85, to the upper flanges of the I-beams 36, and is welded, as at 86, to the upper flanges of the I-beams 67. Also, the bull gear is desirably detachably bolted, as at 87, to the side frame members and end frame members 35 and 36. It will be evident from the drawings and from the description above appearing that the assembly including the car body or frame and the bull gear is detachable into a plurality of separate units of said car body or

frame, which separate units are, each of the side frame members 35, each of the end frame members 36 integrally attached to one diametrical half of the bull gear and to a pair of adjacent I-beams 67, each of the channel pieces 65, and the I-beams 56 and 57 integrally connected by the reinforcing plates 61 and 62. When said reinforcing plates 61 and 62 are detachable, each of the I-beams 55 and 56 is a separate unit of the car body or frame. Obviously in the disclosure as made, the plates 63 are integral with the channel members 65, the plates 50 are integral with the I-beams 36 and 67, the plates 89 and 72 are integral with said I-beams 67, and the plates 74 are integral with said I-beams 36. The several units constituting the car body or frame and the bull gear of the excavating machine can be transported in knocked down condition and assembled at the location where the machine is to find use, as will be understood. Of course, the several units of the car body or frame and the bull gear can be independently constructed when the machine is being manufactured, to be afterwards assembled together and connected in the manner as set forth. That is to say, while the description as given follows a general sequence to produce the car body or frame with bull gear, this sequence can be altered. For example, the two diametrical halves of the bull gear could be welded to the I-beams 36 and 67 either before or after said I-beams are welded to each other and while disassembled from the side frame members 35. Also, the structure including the I-beams 55 and 56 can be assembled with the I-beams 36 either before or after the side frame members and end frame members or I-beams 36 are assembled. And the channels 65 can be assembled into the structure during any preferred stage of its manufacture. What is intended to be said is, that the units of the car body or frame with bull gear as illustrated and described are not only separate units, but are as well units which can be independently made and, speaking generally, independently assembled together.

The revolvable platform of the excavating machine and its manner of support upon the car body or frame through the instrumentality of the king pin and upon the operative rail of the bull gear (the lower rail of the excavating machine) through the instrumentality of the upper rails and the rollers or wheels of the container ring of the machine, will be more clear from Figs. 1 to 5, 6, 9 and 13. As there disclosed, the revolvable platform includes parallel, spaced apart frame members or I-beams 90 extending the length of said platform, and shorter transversely extending, spaced apart I-beams 91, channel members 92 and reinforcing plates 93 connecting said I-beams 90 to each other. The opposite end portions of the members 91, 92 and 93 are welded to the I-beams 90, respectively. As shown more clearly in Figs. 4 and 5, the upper and lower flanges of I-beams 91 and channel members 92 are cut away to terminate flush with the upper and lower flanges of the I-beams 93, and the body portions or webs of said I-beams 91 and channel members 92 meet the body portions or webs of said I-beams 90 and span the distance between the upper and lower flanges of the I-beams 90. The welding of said members 91, 92 and 93 to the I-beams 90 is performed in any suitable manner. The I-beams 90 may include reinforcing webs 94. A floor plate, or plates, of the revolvable platform consists of a sheet, or sheets, of metal 95 which is welded to the upper

flanges of the I-beams 90 and 91, as well as to the channel members 92 and the reinforcing plates 93. Right and left walkways 96, at the outer sides of the I-beams 90 and 91, are detachably bolted, as at 97, to the upper, outer flanges of said I-beams 90. A longitudinally extending channel member 98 is welded to the outer portion of each walkway 96, and each walkway structure additionally includes 10 bracing plates 99 which are welded to the walkways 96 and to the channel members 98. The bracing plates 99 are detachably bolted to the I-beams 99, or to reinforcing plates upon said I-beams 90, as denoted at 100. At the rearward 15 end of the platform there is a depending portion 101 which is a continuation of one of the reinforcing plates 93, and right and left bracing plates 99 at this same end of the platform are detachably bolted, as at 100, to said depending 20 portion 101 and the reinforcing plate 93 integral therewith. Thus each walkway structure is detachable from the remainder of the revolvable platform. A vertical reinforcing web 102 is welded to the lower portion of each I-beam 90 and 25 to the depending portion 101. See Figs. 3 and 4.

The platform of the excavating machine is revolvably mounted by employment of a king pin 103 upon the car body or frame, upper rails 104 upon said platform, and rollers or wheels 105, engaging the operative rail 81 of the bull gear and engaged by said upper rails 104, upon a container ring denoted generally at 106.

The king pin 103 is bolted as at 64 and 107 to the upper flanges of the I-beams 55 and 56 and 35 extends vertically upward. Said king pin may additionally be welded to said I-beams 55 and 56, as well as to the reinforcing plates 61 and 62. The lower portion of the king pin is of rectilinear conformation, and the upper portion 108 thereof 40 is of reduced, cylindrical shape. Said upper portion 108 of the king pin is directly above the longitudinal and transverse center of the car body or frame as disclosed.

As will be more clear from Fig. 5, parallel, 45 spaced apart reinforcing plates 109 extend between intermediate I-beams 91 which are adjacent each other, and said reinforcing plates 109 are welded, as at 110, to said I-beams. A plate 111 is welded to the bottom surface of the lower 50 flanges of each of the mentioned I-beams 91, as at 112, and divergent bars 113 are welded to each plate 111, as at 114. The bars 113 are disposed in a horizontal plane and are welded, as at 115, to plates 116 themselves welded, as at 117, 55 in the instance of one set of plates 116, to a channel member 92, and in the instance of the other set of plates 116, to an I-beam 91 next adjacent an I-beam having a plate 111. The welded-in units each consisting of the plate 111, divergent bars 113 and plates 116 obviously constitute reinforcing members of the platform.

A bearing plate 118 is bolted, as at 119, against the lower surfaces of the plates 111 at location 60 beneath the flanges of the I-beams 91 having said plates 111, the bolts 119 passing through the flanges of the I-beams as well as through the plates 111. Said bearing plate 118 includes a downwardly extending bearing portion 120 which is situated at the transverse center of the revolvable platform, but at location considerably closer to the front or boom end of the platform than to the rear end thereof, whereby to balance said platform upon its axis against the added weight of the boom, as will be understood. The bearing portion 120 is rotatably mounted upon the cylind-

rical portion 108 of the king pin, numeral 121 denoting a bushing in the bearing portion and about the king pin. As will become evident, no means is needed at the location of the king pin and the bearing portion 120 thereon to limit downward movement of said bearing portion upon said king pin, because downward movement of the platform is limited by the engagement of the upper rails 104 with the rollers or wheels 105 and the engagement of said rollers or wheels with the operative rail of the bull gear. At the upper side of the bearing plate 118, however, there is disclosed a split collar 122 lying in an annular groove upon the cylindrical portion 108 of the king pin, a washer 123 being situated between 15 said split collar and said bearing plate.

As will be more clear from Figs. 1, 4, 5 and 13, a pair of plates, denoted 124 and 125, respectively, extend transversely of the platform in spaced relation to each other, and are suitably welded 20 to the lower surface of said platform; that is, to the lower surfaces of some or all of the members 90, 91, 92, 93 and 94. An upper rail 104 is welded and/or bolted to each of said plates 124, 125 to extend vertically downward from the platform. 25 Each upper rail is concentric with the axis of the platform, and said upper rails are disposed directly above the operative rail 81 of the bull gear, which operative rail constitutes the lower rail of the excavating machine. The upper rails 104 30 could be a single unbroken annular rail, but separate rails arranged diametrically opposite each other and each describing an arc of not more than 90° are sufficient and preferable. The circumference which said upper rails 104 would 35 describe if continued is exactly equal to and vertically above the circumference described by the bull gear rail 81.

The container ring 106 consists of inner and outer continuous bands, denoted 126 and 127, respectively, and the rollers or wheels 105 are freely rotatable on shafts 128 suitably mounted in said inner and outer bands at equally spaced distances apart. Each band 126, 127 can consist of a single strip or piece of metal, or of several strips or 40 pieces of metal connected together in well known or preferred manner. The shafts 128 for the different rollers or wheels 105 retain the bands 126 and 127 in fixed relation to each other. As disclosed more clearly in Fig. 9, each shaft 128 is 45 welded, at 129, to the outer band 127, and includes a reduced threaded portion 130 passing through the inner band 126, said reduced portion providing a circumferential shoulder 131 adjacent said inner band 126. A nut 132 upon each threaded portion 130 is turned home against the inner band 126 to force it against the corresponding shoulder 131. The container ring supports the rollers or wheels 105 in a circumference having 50 diameter equal to that of the circumference described by the bull gear rail 81, as well as to that of the circumference described by the upper rails 104 continued, and the traveling surface of each roller or wheel 105 is suitably grooved, as indicated at 133, to fit each of said rails 81 and 104. Clearly, when the upper rails 104 are fitted to the upper portions of all of the rollers or wheels 105 and the lower portions of all of said rollers or 55 wheels are fitted to the operative rail 81 of the bull gear, the platform is mounted for revolvable movement upon the car body or frame about the king pin as an axis, said king pin cooperating in the structure to keep the upper and lower rails properly centered and directly in line with the 60 rollers or wheels 105.

Mechanism for revolving the platform in either direction is very clearly disclosed in Figs. 1, 2, 4, 5, 6 and 13. As there disclosed, a bearing plate 134 is bolted, as at 135, to the floor plate 95 and to upper flanges upon adjacent I-beam 91 and channel member 92 which are near the forward or boom end of the platform. Said bearing plate 134 includes a bearing portion 136 extending upwardly therefrom a short distance, and a longer bearing portion 137 extending downwardly through openings in the floor plate 95 and the plate 125 to position somewhat below the platform. A retainer plate 138 for the bearing portion 137 is welded to the lower surface of the plate 125, and includes an opening 139 in which an annular boss 140 upon the bearing portion 137 is tightly fitted. Thus the bearing portion 137 is very rigidly attached to the lower portion of the platform without the use of bolts or other detachable members which are liable to jar or become loose when the excavating machine is in extended use. A vertical shaft 141 is fitted to the bearing portions 136 and 137 and extends a short distance beyond the ends of said bearing portions both above and below the platform. A bevel gear 142 is suitably fixed to the upper portion of the vertical shaft 141, and a pinion 143 is suitably fixed to the lower portion of said vertical shaft. Said pinion 143 meshes with the gear surface or toothed portion 79 of the bull gear. Numeral 144 denotes a bushing upon the shaft 141 and in the bearing portion 136, said bushing also extending to position between the bevel gear 142 and said bearing portion 136, and 145 indicates a bushing upon said shaft 141 and in the lower part of the bearing portion 137. An electric motor 146 is suitably supported upon the platform. Said motor 146 is set up to drive a pinion 147 in either direction, through the instrumentality of reducing gearing 148. The motor 146 can be a reversible motor, or the mechanism 148 can include devices for reversing the direction of rotation of the pinion 147. Said pinion 147 meshes with the bevel gear 142 to drive said bevel gear. It is to be understood that any other suitable means different from the means illustrated and described can be employed to rotate the bevel gear 142 selectively in either direction. Evidently, when the pinion 147 is turned, the bevel gear 142 will also be turned to rotate the shaft 141 and the pinion 143 fixed to said shaft. Rotation of said pinion 143 causes it to ride along the gear surface or toothed portion of the bull gear fixed to the car body or frame, and thus causes the platform to be revolved upon its axis a distance corresponding to the extent of rotation of the shaft 141, as will be apparent. The revolvable platform supports a mast, denoted generally at 149, a back brace, indicated 60 generally at 150, said mast and back brace being associated with each other to provide a mast structure for the machine, and a boom, represented generally at 151. Also, the floor plate of said platform suitably supports front, middle and rear drums, denoted 152, 153 and 154, respectively, which drums are of any ordinary or preferred construction, and an electric motor 275 for the drums. Usual cables 155 and 156 extend from the drums to control the boom and the bucket or dipper (not shown) of the excavating machine. Said cables can be arranged in any convenient and satisfactory manner, forming no part of the invention, to operate and control the boom and the bucket or dipper. Speaking generally, there 70 are sheaves 157 freely mounted upon the upper

portion of the mast structure for cables 155, and said cables 155 are associated with sheaves 158 and with links 159 having said sheaves 158, said links being suitably pivoted, as at 160, to an upper part of the boom. Also, there are intermediate and lower sheaves, indicated 161 and 162, respectively, freely mounted upon the mast and upon which cables 156 travel. And the upper end of the boom includes sheaves 163 for cables 156, numeral 164 representing an ordinary or preferred type of cable guard for said sheaves 163.

The boom 151 is of the novel and improved construction and is mounted upon the platform of the excavating machine in the novel and improved manner as now to be described. The 15 structure of the boom and its mounting means is more clearly disclosed in Figs. 1, 2, 4, 5, 13 to 22 and 28. As there shown, said boom is constructed in bottom and top sections each including longitudinally extending angle pieces, there 20 being an angle piece having the apex thereof defining each of the four corners of the boom. The angle pieces of the boom adjacent to or at the upper surface thereof are denoted 165, 165, and the angle pieces adjacent to or at the lower 25 surface of the boom are represented 166, 166. The boom is, speaking generally, of greater width than thickness, the angle pieces 165, 165 and the angle pieces 166, 166, respectively, being spaced apart at greater distance than is each upper 30 angle piece 165 and the adjacent lower angle piece 166.

The bottom section of the boom includes, in addition to the upper angle pieces 165, 165 and the lower angle pieces 166, 166, a series of obliquely disposed T-bars 167 at each side of the boom, said T-bars 167 being welded to inner surfaces of adjacent angle pieces 165, 166, as at 168, with the body portions of the T-bars extending inwardly as shown. At each side of the boom, alternate T-bars 167 are parallel with each other and adjacent T-bars 167 are in oblique relation to each other to all but meet, as in Fig. 18, at location where said T-bars are welded to the angle pieces. The T-bars 167 at one side of the boom are in staggered relation to the T-bars 167 at the other side of said boom, as shown more clearly in Fig. 14, so that a lattice effect is the result.

so that a lattice effect is the result.

The bottom section of the boom also includes a series of T-bars at the upper and lower surfaces of said boom. Of these T-bars, 169 denotes upper, obliquely disposed T-bars each having its bottom end welded to a lower portion of an angle piece 165, and 170 represents similar lower, obliquely disposed T-bars each having its bottom end welded to a lower portion of an angle piece 166. The T-bars 169 and 170 are at the outer surfaces of the angle pieces and the body portions of said T-bars 169 and 170 extend outwardly from the boom. The upper end of each oblique T-bar 169 is welded to an upper plate 171, and the upper end of each oblique T-bar 170 is welded to a lower plate 172, said plates 171 and 172 being at the transverse center of the boom and at the elevation of the angle pieces 165 and 166, respectively. An upper T-bar 173 extends transversely of the boom and has its opposite ends welded to the inner surfaces of the angle pieces 165, 165, and a lower T-bar 174, directly beneath the T-bar 173, also extends transversely of the boom and has its opposite ends welded to the inner surfaces of the angle pieces 166, 166. The body portions of the T-bars 173 and 174 extend inwardly of the boom. The plate 171 is welded to the T-bar 173 75

and the plate 172 is welded to the T-bar 174. A reinforcing plate 175 at the transverse center of the boom has its opposite ends welded to the T-bars 173 and 174, respectively. Each of upper, 5 obliquely disposed T-bars 176 has its bottom end welded to the plate 171 and its top end welded to an angle piece 165, and each of lower, obliquely disposed T-bars 177 has its bottom end welded to the plate 172 and its top end welded to an 10 angle piece 166. The body portions of the T-bars 176 and 177 extend inwardly of the boom. An upper T-bar 178 extends transversely of the boom and has its opposite ends welded to the inner surfaces of the angle pieces 165, 165, and a 15 similar lower T-bar has its opposite ends welded to the inner surfaces of the angle pieces 166, 166. The body portions of the T-bar 178 and the similar T-bar directly beneath said T-bar 178 extend inwardly of the boom. The T-bar 178 20 all but meets the top ends of the T-bars 176 as shown more clearly in Fig. 19, and the lower T-bar which is similar to the T-bar 178 bears this same relation to the top ends of the T-bars 177. A plate 179 is welded to the upper surface 25 of the flange of the T-bar 178 at the transverse center of the boom, and a similar plate is welded to the lower surface of the flange of the T-bar similar to the T-bar 178 also at the transverse center of the boom. Each of upper, obliquely disposed T-bars 180 has its bottom end welded to the plate 179 and its top end welded to an angle piece 165, and each of lower obliquely disposed T-bars similar to the T-bars 180 has its bottom 30 end welded to a lower plate similar to the plate 179 and directly therebeneath and its top end welded to an angle piece 166. The body portions of the T-bars 180 and the lower T-bars similar thereto extend inwardly of the boom. An upper T-bar 181 extends transversely of the boom and 35 has its opposite ends welded to the inner surfaces of the angle pieces 165, 165, and a similar lower T-bar has its opposite ends welded to the inner surfaces of the angle pieces 166, 166. The body portions of the T-bar 181 and the similar T-bar 40 directly opposite said T-bar 181 extend inwardly of the boom. The T-bar 181 all but meets the top ends of the T-bars 180, and the lower T-bar which is similar to the T-bar 181 bears this same relation to the top ends of the T-bars beneath 45 50 and similar to the T-bars 180. A plate 182 is welded to the upper surface of the flange of the T-bar 181 at the transverse center of the boom, and a similar plate is welded to the lower surface of the flange of the T-bar similar to the T-bar 55 55 181 also at the transverse center of the boom. Each of upper, obliquely disposed T-bars 183 has its bottom end welded to the plate 182 and its top end welded to an angle piece 165, and each of lower obliquely disposed T-bars similar to the T-bars 183 has its bottom end welded to a lower plate similar to the plate 182 and directly therebeneath and its top end welded to an angle piece 60 65 66. The body portions of the T-bars 183 and the lower T-bars similar thereto extend inwardly of the boom. An upper T-bar 184 extends transversely of the boom and has its opposite ends welded to the inner surfaces of the angle pieces 165, 165, and a similar lower T-bar has its opposite ends welded to the inner surfaces of the angle pieces 166, 166. The body portions of the T-bar 184 and the similar T-bar directly beneath said T-bar 184 extend inwardly of the boom. The T-bar 184 all but meets the top ends of the T-bars 183, and the lower T-bar which is similar 70 75 to the T-bar 184 bears this same relation to the

top ends of the T-bars beneath and similar to the T-bars 183. A series of obliquely disposed T-bars 185 at the upper and lower surfaces of the boom are welded to inner surfaces of adjacent angle pieces 165, 165 and 166, 166, respectively, 5 with the body portions of said T-bars 185 extending inwardly of the boom. At each of the upper and lower surfaces of the boom, alternate T-bars 185 are parallel with each other and adjacent T-bars 185 are in oblique relation to each other to all but meet, as in Fig. 19, where said T-bars are welded to the angle pieces. The T-bars 185 opposite each other, at the upper and lower surfaces of the boom, are in staggered relation, as shown very clearly in said Fig. 19 so that 10 15 a lattice effect is the result.

The bottom section of the boom is joined to the top section thereof at location just above the T-bars 167 and 185, said bottom section permanently supporting means for making the connection 20 between the sections. At the location of the joint between said sections, the bottom section is reinforced by eight plates, including upper plates 186, 186 attached to the horizontal arms of the angle pieces 165, 165, upper plates 187, 187 attached 25 to the vertical arms of said angle pieces 165, 165, lower plates 188, 188 attached to the horizontal arms of the angle pieces 166, 166, and lower plates 189, 189 attached to the vertical arms of said angle pieces 166, 166. The plates 186, 187, 30 35 188 and 189 are on the outer surfaces of the arms of the angle pieces and terminate approximately flush with the apices of said angle pieces. As shown, said plates and angle pieces are secured together by rivets 190, but could be welded to each 40 other. Each plate 186, 187, 188 and 189 includes portions thereof extending upwardly beyond the top of, and inwardly beyond the inner edge, the angle piece arm carrying said plate. An upper T-bar 191, arranged transversely of the boom, 45 has the opposite ends of its flanges welded to the inner surfaces of the inwardly extending portions of the plates 186, 188, with the body portion of said T-bar 191 extending inwardly of the boom. A lower T-bar 192, also arranged transversely 50 of the boom and disposed opposite said T-bar 191, has the opposite ends of its flanges welded to the inner surfaces of the inwardly extending portions of the plates 188, 188, with the body portion of said T-bar 192 extending inwardly of the boom. And each of side T-bars 193, in the plane 55 of the T-bars 191 and 192, has the opposite ends of its flanges welded to the inner surfaces of the inwardly extending portions of adjacent plates 187, 189, with the body portions of said T-bars 193 extending inwardly of the boom. Bracing plates 194, one adjacent each corner of the boom, are welded to the opposite ends of the body portions of the T-bars 191, 193 and 192, 193, respectively, and a T-bar 195 extends between opposite 60 65 bracing plates 194 and has its ends welded thereto. The lower parts of the angle pieces 165, 165, 166 and 166 of the top section of the boom are provided with bolt holes 196 which are adapted 70 75 to align with bolt holes 197 in the upward extensions of the plates 186, 187, 188 and 189. Bolts 198 in said bolt holes 196 and 197 detachably connect the bottom and top sections of the boom together with corresponding angle pieces 70 of the different boom sections in alignment, as is apparent. The lower part of the top section of the boom includes an oblique T-bar 199 at one side of said boom welded at its upper end to an angle piece 165 and having bolt holes 200 at 75

its lower end adapted to aline with bolt holes 204 in a plate 189. Bolts 202 connect said T-bar 199 with said plate 189. An oblique T-bar 203 at the other side of the boom, opposite the T-bar 199, is welded at its upper end to an angle piece 166 and has bolt holes 204 at its lower end adapted to aline with bolt holes 205 in a plate 187. Bolts 206 connect said T-bar 203 with said plate 187. An oblique T-bar 207 at the upper surface of the lower part of the top section of the boom is welded at its upper end to an angle piece 165 and bolted at 208 to a plate 186. An oblique T-bar 209 at the lower surface of the lower part of the top section of the boom, opposite the T-bar 207, is welded at its upper end to an angle piece 166 and bolted at 210 to a plate 188. The body portions of the T-bars 199, 203, 207 and 209 extend inwardly of the boom, and the flanges of said T-bars are cut away at the locations where the T-bars are bolted.

Directly above the T-bars 199 and 203 the top section of the boom includes an additional series of obliquely disposed T-bars 167 at each side of said boom, which additional T-bars 167 are welded into the boom structure and have the same relative arrangement to the angle pieces and to each other as hereinbefore described.

Directly above the T-bars 207 and 209 the top section of the boom includes a series of T-bars at the upper and lower surfaces of said boom. Of these T-bars, 211 denotes an upper T-bar extending transversely of the boom and having its opposite ends welded to the inner surfaces of the angle pieces 165, 165. A lower T-bar, similar to the T-bar 211 and directly opposite said T-bar 211, has its opposite ends welded to the inner surfaces of the angle pieces 166, 166. The body portions of the T-bar 211 and the similar, directly opposite T-bar extend inwardly of the boom. Directly above the T-bar 211 and the lower, similar T-bar opposite said T-bar 211, the top section of the boom includes a series of obliquely disposed T-bars 212 at the upper and lower surfaces of said boom. Upper T-bars 212 are welded to the inner surfaces of the angle pieces 165, 165, and lower T-bars 212 are welded to the inner surfaces of the angle pieces 166, 166, with the body portions of all of said T-bars 212 extending inwardly of the boom. At each of the upper and lower surfaces of the boom, alternate T-bars 212 are parallel with each other and adjacent T-bars 212 are in oblique relation to each other to all but meet, as shown in Fig. 20, at location where said T-bars are welded to the angle pieces. The T-bars 212 at the upper surface of the boom are in staggered relation to the T-bars 212 at the lower surface of said boom, so that a lattice effect is the result.

Reinforcing plates 213, one at each side of the upper part of the top section of the boom, are welded to the outer surfaces of upper and lower angle pieces 165, 166 and 165, 166, respectively, as shown more clearly in Figs. 14 and 20. The outer end of each plate 213 terminates about flush with the upper or outer ends of the angle pieces of the boom. The inner end portion of each plate 213 extends to position along the boom below the elevation of one or more T-bars 212 and additional T-bars 161. The upper edge of each plate 213 terminates about flush with the upper surface of the boom. And the lower portion of each plate 213 extends below the lower surface of the boom. A reinforcing plate 214 extends transversely of the upper or outer end of the boom and is welded to the ends of the angle

pieces 165, 165, 166, 166. Small plates 215 are welded to the outer surfaces of the plates 213 at location adjacent to the upper or outer end of the boom, and a shaft 216 for the sheaves 163 is suitably mounted in each of the opposite plates 213 and 215. Small plates 217 are welded to the outer surfaces of the plates 213 at location slightly inwardly from the plates 215, and support, together with said plates 213, the pins or pivots 160 which attach the links 159 to the boom. A reinforcing plate 218 extends transversely of the boom at the inner sides of the plates 217 and adjacent to the T-bars 212. Said plate 218 is welded to the inner surfaces of the angle pieces.

Reinforcing plates 219, one at the upper surface and one at the lower surface of the boom, extend transversely of said boom and are welded to the outer surfaces of arms of the angle pieces 165, 165 and 165, 166, respectively. The outer extremities of the plates 219 terminate just below the sheaves 163, and the inner end portions of said plates 219 extend to position along the boom below the elevation of one or more T-bars 212 and additional T-bars 161.

While the illustration as made in the drawings and the description as given are of a boom consisting of two sections, one a lower section and the other an upper section, attention is called to the fact that the boom can be constructed as a single section extending the length of said boom, or can consist of more than two sections. In the latter event, additional sections could be connected into the boom structure in the manner as hereinbefore fully set forth, or in any other suitable and preferred manner.

The inner or lower end portion of the bottom section of the boom carries supporting bearing members 220, one at each side of the boom, for said boom. Longitudinally extending reinforcing plates 221, one at each side of the boom, are welded to the outer surfaces of the angle pieces 165, 166 and 165, 166, respectively, and each bearing member 220 includes an integral web or attachment portion 222 which is riveted, as at 223, 45 to the lower or bottom parts of the adjacent plate 221 and the adjacent angle pieces 165, 166. The webs or attachment portions 222 are at the inner sides of the angle pieces, and each web or attachment portion 222 has relation to its bearing member 220 and to the adjacent angle pieces 165, 166 situating the bearing members 220 at the midthickness of the boom. Each bearing member 220 is desirably in a plane including the angle pieces 165, 166 at the corresponding side of the boom. Numeral 224 denotes openings providing opposed bearing surfaces of each bearing member 220, all of which bearing surfaces 224 are in a line extending transversely of the boom at the midthickness thereof.

At the forward or boom end of the platform of the excavating machine, each longitudinal I-beam 90 includes elongated slots 225 in the upper flanges thereof which open to the forward or boom ends of said I-beams 90 and extend rearwardly at the opposite sides of the body portions of said I-beams, as shown very clearly in Fig. 28. A plate 226 is welded to each of the opposite surfaces of the body portion of each I-beam 90 and extends upwardly through an elongated slot 70 225, numeral 227 denoting portions of the plates 226 extending above the I-beams 90. A smaller plate 228 is positioned between the portions 227 of the plates 226 on each I-beam 90 and is welded to said portions 227. The lower end of each 75

plate 228 is contiguous with the corresponding I-beam 90 and may also be welded to said I-beam. Each structure as described, at either side of the forward or boom end of the platform and including the plates 226 with upward extensions 227 and the plates 228 between said extensions 227, constitutes means cooperating to support both the mast 149 and the boom 151 upon the platform. That is to say, the elements 227, 228, 227, 10 which are integrally connected and are integral with the I-beams 90, provide spaced apart bearing blocks, denoted 229, upon which both the mast 149 and the boom 151 are mounted. At the forward or boom end of the platform, a transverse plate 276 is welded to the forward end of each I-beam 90 and to each bearing block 229. The plates 276 support bracing plates 99.

Each bearing block 229 includes an opening 230 at the forward or boom end thereof, said openings 230 lying in a line extending transversely of the platform. The boom is mounted upon the bearing blocks 229 by means of pins 231, one for each bearing block on the platform and each bearing member on the boom, which pins are suitably retained in the openings 224 of the bearing members 220 and in the openings 230 of the bearing blocks. Each bearing block 229 is between opposed bearing surfaces of a bearing member 220, and washers 232 are situated between the bearing blocks and the adjacent bearing surfaces of the bearing members.

The mast 149 and the back brace 150 are of the novel and improved construction and are mounted upon the platform of the excavating machine and connected with each other in the novel and improved manner as now to be described. The structure of the mast and of the back brace and their mounting means, and of the means connecting the upper portions of said mast and back brace with each other, is plainly disclosed in Figs. 1, 2, 4, 5, 13, 23 to 27 and 29. As there shown, said mast includes longitudinally extending channel pieces 233 having their flanges projecting outwardly of the mast. Said channel pieces 233 are at the opposite sides of the mast and converge upwardly, and a plurality of strengthening and reinforcing elements interconnect the channel pieces. Said mast includes, in addition to the channel pieces 233, plates 234 welded to the opposite upper flanges of the channel pieces at the bottom of said flanges, and plates 235 welded to the opposite lower flanges of the channel pieces 233 at the bottoms of said flanges. The plates 234, 234 and 235, 235, respectively, extend inwardly of the mast toward each other. Upper and lower transverse channel bars 255 have their opposite end portions welded to the outer surfaces of the plates 234, 234 and 235, 235, respectively. The mast also includes plates 236, above the plates 234 and spaced therefrom, welded to the opposite upper flanges of the channel pieces, and plates 237, above the plates 235 and opposite the plates 236, welded to the opposite lower flanges of the channel pieces. The plates 236, 236 and 237, 237, respectively, likewise extend inwardly of the mast toward each other. Oppositely disposed channel pieces 238 are situated between the channel pieces 233, in spaced relation to each other and to said channel pieces 233, at the elevation of the plates 234, 235, 236 and 237, and have their flanges projecting outwardly. The upper parts of the body portions of the channel pieces 238 are parallel, and lower parts of said channel pieces 238 diverge downwardly and terminate in close proximity to

the channel pieces 233. All of the channel pieces 233, 233, 238 and 238 are in a single plane passing longitudinally through the mast. The opposite flanges of the channel pieces 238 are welded to all of the plates 234, 235, 236 and 237. Said channel pieces 238 include suitable bearings for the shafts 239 of the sheaves 161 and 162.

A transverse channel bar 240 at the elevation of the plates 236 and 237 has its opposite end portions welded to the body portions of the channel pieces 233, to the top ends of the channel pieces 238, and to the inner surfaces of all of the plates 236 and 237. A series of obliquely disposed T-bars 241 at the upper and lower surfaces of the mast are welded to opposite flanges of the channel pieces 233 at location directly above the channel bar 240, with the body portions of said T-bars 241 extending outwardly of the mast. At each of the upper and lower surfaces of the mast, alternate T-bars 241 are parallel with each other and adjacent T-bars 241 are in oblique relation to each other to all but meet, as shown in Fig. 26, where said T-bars are welded to the flanges of the channel pieces. The T-bars 241 opposite each other, at the upper and lower surfaces of the mast, are in staggered relation, as shown quite plainly in said Fig. 26, so that a lattice effect is the result.

Reinforcing plates 242, one at the upper and one at the lower side of the mast near the top thereof and directly above the T-bars 241, are welded to the opposite flanges of the channel pieces 233. Said plates 242 are cut away at 243 to clear the sheaves 157. A shaft 244 for said sheaves 157 is mounted in suitable bearings in the channel pieces 233 at location above and adjacent to the plates 242 and not far from the upper end of the mast. A reinforcing channel bar 245 extends transversely of the top end of the mast and is welded to the ends of the channel pieces 233. Spaced apart, vertical plates 246 are welded to the inner surfaces of the body portions of the channel pieces 233, and extend downwardly toward the back brace 150, as will be more clear from Figs. 1, 23 and 27. Each plate 246 is welded to two smaller plates 247, said plates 247 in each instance being at the lower edge of and at the opposite sides of the plate 246 by which they are supported. Said plates 247, 246, 247 provide means upon the mast for attaching said mast and the back brace to each other in a manner which will be set forth.

The downwardly divergent portions of the channel pieces 238 merge at their lower ends into short bottom parts 248 of said channel pieces 238, including a bottom part 248 having its body portion arranged adjacent to and parallel with the body portion of the bottom part of each channel piece 233. A small plate 249 is welded to the inner surface of the body portion of each bottom part 248, and a small plate 250 is welded to the outer surface of the body portion of the bottom part of each channel piece 233, as shown more clearly in Fig. 29. Each bottom part 248 cooperates with the directly adjacent portion of the channel piece 233 to provide a bearing or supporting member 251 for the mast, the plates 249 and 250 in each instance constituting reinforcements of the bearing or supporting member. Numeral 252 denotes openings through the elements of the bearing or supporting members 251, providing opposed mounting surfaces of each bearing or supporting member, all of which mounting surfaces 75

are in a line extending transversely of the mast, as well as in the plane of the mast.

Each bearing block 229, including an opening 230 for mounting the boom, also includes an opening 253 for mounting the mast upon the platform. The openings 253 are at the rear of the openings 230, and lie in a line extending transversely of the platform. The mast is mounted upon the bearing blocks 229 by means of pins 254, one for each bearing block on the platform and each bearing or supporting member on the mast, which pins are suitably retained in the openings 252 of the bearing or supporting members 251 and the openings 253 of the bearing blocks. Each bearing block 229 is between opposed mounting surfaces of a bearing or supporting member 251.

The back brace 150 includes longitudinally extending I-beams 256 at the opposite sides of said back brace. Lower portions 257 of said I-beams 256 are parallel, and upper portions 258 of the I-beams converge upwardly, numeral 259 denoting a bend line of each I-beam 256 where the lower and upper portions 257 and 258 thereof meet. Strengthening and reinforcing elements interconnect the I-beams 256. Said back brace includes, in addition to the I-beams 256, a transverse I-beam 260 extending between said I-beams 256 at the location of the bends 259, said I-beam 260 having its opposite end portions welded to the I-beams 256. The brace also includes plates 261 welded to the opposite upper flanges of the I-beams 256 and 260, and plates 262 welded to the opposite lower flanges of said I-beams 256 and 260.

Reinforcing plates 263, one at the upper and one at the lower side of the back brace near the top thereof, are welded to the opposite flanges of the converging portions 258 of the I-beams 256. The upper end of the body portion of each I-beam 256 supports two small plates 264, said plates 264 in each instance being at the opposite sides of said body portion of the I-beam 256 by which they are supported and terminating flush with the upper end of said I-beam, as will be more clear from Fig. 25. The plates 264 are welded to the I-beams. A larger plate 265 is welded to the outer surfaces of each plate 264, and said plates 265 in each instance include spaced apart portions 266 extending vertically upward from the corresponding I-beam 256. To attach the back brace and the mast to each other, each set of plates 247, 246, 247 upon the mast is positioned between a set of spaced apart portions 266 upon the back brace, and a pin 267 is inserted and fastened in openings 268 through said sets of plates and said sets of spaced apart portions.

The platform of the excavating machine includes a transverse I-beam 269 welded to the lower surfaces of the I-beams 90 and extending beyond the outer sides of said I-beams 90, as shown more clearly in Figs. 1, 4 and 23. The lower portions of the parallel parts 257 of the I-beams 256 extend downwardly through openings 270 in the walkways 96. See Figs. 2 and 23. The lower end of the body portion of each I-beam 256 supports two small plates 271, said plates 271 in each instance being at the opposite sides of said body portion of the I-beam by which supported and terminating flush with the lower end of said I-beam, as will be more clear from Fig. 24. The flanges of each I-beam 256 are cut away at the elevation of said plates 271, and said plates are welded to said I-beams. Spaced apart, vertical

plates 272 are fitted upon and welded to the opposite end portions of the transverse I-beam 269, as shown very clearly in Figs. 1 and 23. Said vertical plates 272 extend upwardly above the I-beams 269. To attach the back brace to the platform, the lower end of each I-beam 256 with plates 271 welded thereto is positioned between a set of spaced apart plates 272 upon the I-beam 269, and each of pins 273, one for each connection to be made, is inserted and fastened in openings 274 through each set of plates 272 and through each I-beam 256 and the plates 271 thereon. The connections between the I-beams 256 and the platform are in a horizontal line extending transversely of the platform.

Both the mast 149 and the back brace 150 lie in a vertical plane passed longitudinally through the platform. Said mast slants downwardly at desired angle from rear toward front of the platform, and said back brace slants downwardly at desired angle from front toward rear of said platform, to provide a mast structure the upper portions of which are connected together at location above and between the locations where said mast and said back brace are mounted upon the platform, as is customary.

What is claimed is:

1. In an excavating machine, a car body, a platform, means supporting said platform upon said car body, and means for revolving said platform upon its support, said last mentioned means comprising a gear surface upon said car body, a pinion engaging said gear surface, a shaft carrying said pinion, devices for rotating said shaft, a bearing for said shaft, a plate integral with said bearing and bolted to an upper portion of said platform, and a plate welded to a lower portion of said platform, said bearing extending downwardly through an opening in said last mentioned plate and being tightly fitted to said opening, and said shaft projecting beyond the opposite ends of said bearing.

2. In an excavating machine, a bull gear comprising a plurality of part-circle elements adapted to be detachably connected, and a member 45 consisting of separable parts for supporting said bull gear, each of said part-circle elements consisting of a part-circle, upstanding portion, a second part-circle, upstanding portion having a horizontally disposed lower rail surface serving as a 50 support in said excavating machine, said part-circle portions being in concentric relation, a gear surface upon one of said part-circle portions, and a connecting web between said part-circle portions at the bases thereof and resting upon said 55 supporting member, the different connecting webs, respectively, being secured to different separable parts of said supporting member.

3. An excavating machine comprising a car body, a platform upon said car body, a member 60 revolvably supporting said platform upon said car body, an upstanding lower rail portion upon said car body and carrying an upstanding portion having a gear surface, said lower rail portion being concentric with said supporting member and 65 said gear surface, a web integrally connecting the bases of said upstanding lower rail portion and said upstanding portion having said gear surface, said web resting upon and being secured to said car body, an upper rail portion upon said platform above said lower rail portion, a roller member 70 engaging said lower rail portion and supporting said upper rail portion, and means engaging said gear surface for revolving said platform.

4. In an excavating machine, a car body, and 75

- a bull gear constituted as an integral structure consisting of an inner curvilinear portion providing an internal vertically disposed gear surface, an outer curvilinear upstanding portion providing an operative rail constituting a lower rail for said excavating machine adapted to support a revolvable platform of the machine, and a horizontal web portion integrally connecting said inner curvilinear portion with a lower part of said outer curvilinear portion, said outer curvilinear portion extending upwardly from said web portion, and the web portion including a bottom surface supported upon said car body.
5. In an excavating machine, a car body, and a bull gear supported upon an upper surface of said car body, said bull gear being constituted as an integral structure adapted to be fastened down upon said car body and comprising a web portion, an operative rail at one side of said web portion and integral therewith and extending upwardly from the web portion and the car body, and a portion at the opposite side of said web portion and integral therewith and providing a gear surface in spaced relation to said operative rail.
10. In an excavating machine, a knock-down car body structure comprising longitudinally extending side frame members, transversely extending end frame members, means for detachably connecting meeting portions of said side frame members and said end frame members to each other, and a bull gear consisting of a plurality of separate part-circle members each constituted as an integral structure independently secured to a frame member, each part-circle member comprising a connecting web, a part-circle element at one side of said connecting web and extending upwardly therefrom and providing part of an operative rail for said excavating machine, and a second part-circle element at the opposite side of said connecting web and providing a gear surface in spaced and concentric relation to said operative rail.
15. In an excavating machine, the combination with a knock-down car body structure comprising longitudinally extending side frame members, transversely extending end frame members, and means for detachably connecting meeting portions of said side frame members and said end frame members to each other, of a bull gear consisting of a plurality of separate part-circle members each constituted as an integral structure separately and independently secured to a frame member, each part-circle member comprising a connecting web resting upon a frame member, a

part-circle element integral with one side of said connecting web and extending upwardly above the plane of the web and providing part of an operative rail for said excavating machine, and a second part-circle element integral with the opposite side of said connecting web and providing a gear surface in spaced and concentric relation to said operative rail.

8. In an excavating machine, a bull gear comprising a plurality of part-circle members adapted to be detachably connected, and a member consisting of separable parts for supporting said bull gear, each of said part-circle members consisting of a part-circle upstanding element, a second part-circle upstanding element having an operative rail surface serving as a support in said excavating machine, said part-circle elements being in concentric relation, a gear surface upon one of said part-circle elements, and a connecting web between and integral with said part-circle elements and below said operative rail, the connecting web of each part-circle member being permanently and independently secured to one of the separable parts of said supporting member.

9. In an excavating machine, a bull gear comprising a plurality of independent part-circle members, and a member consisting of separable parts for supporting said bull gear, each of said part-circle members consisting of a part-circle element, a second part-circle element having an operative rail surface serving as a support in said excavating machine, said part-circle elements being in concentric relation, a gear surface upon one of said part-circle elements, and a connecting web between and integral with said part-circle elements, the connecting web of each part-circle member being permanently and independently secured to one of the separable parts of said supporting member.

10. In an excavating machine, a bull gear comprising a plurality of independent part-circle members, and a member consisting of separable parts for supporting said bull gear, each of said part-circle members consisting of a part-circle element, a second part-circle element having an operative rail surface serving as a support in said excavating machine, said part-circle elements being in concentric relation, a gear surface upon one of said part-circle elements, and a connecting web between and integral with said part-circle elements, each of said part-circle members being permanently and independently secured to one of the separable parts of said supporting member.

ROLF E. LJUNGKULL.
